8 SHEETS—SHEET 2.

The image contains two technical drawings of a mechanical device. The left drawing, labeled 'Fig. 2', shows a side view of a vertical assembly. It features a series of horizontal bars, with the top one labeled '20'. Below these are several horizontal bars labeled '102' and '103'. A vertical plate labeled '30' is positioned to the right of the bars. The right drawing, labeled 'Fig. 9', is a more detailed view of the right side of the device. It shows a vertical plate with several circular holes, each labeled '35'. A horizontal bar labeled '20' is attached to the top of the plate. Below the plate, a series of horizontal bars are labeled '21', '22', and '23'. A vertical pipe labeled '26' is attached to the bottom of the plate. A horizontal pipe labeled '27' is attached to the bottom of the vertical pipe. A small detail drawing at the bottom left shows a cross-section of a component with parts labeled '30', '32', and '33'.

UNITED STATES PATENT OFFICE.

ROBERT F. HUDSON, OF RICHMOND, VIRGINIA.

MACHINE-GUN.

1,386,872.

Specification of Letters Patent.

Patented Aug. 9, 1921.

Application filed March 20, 1919, Serial No. 283,807. Renewed January 3, 1921. Serial No. 434,840.

To all whom it may concern:

Be it known that I, ROBERT F. HUDSON, a citizen of the United States, residing at Richmond, in the county of Henrico and State of Virginia, have invented certain new and useful Improvements in Machine-Guns, of which the following is a specification, reference being had therein to the accompanying drawing.

10 My invention relates to improvements in machine guns; one object of the invention being the provision of positive means by which the cartridge is delivered to the breech of the barrel, is retained in such position during the firing operation, and the empty shell or even in case the cartridge should be unexploded, it is removed from the breech of the barrel and released to move or fall in an opposite direction to the oncoming new cartridges.

15 A further object of this invention is the provision of a machine gun in which the firing mechanisms are preferably arranged in pairs and whereby a plurality of barrels 25 may be employed so that an exceedingly effective defensive weapon can be provided and one which will positively act and in which one or more barrels will be discharged at a time.

20 A still further object of this invention is the provision of a machine gun which eliminates the defects due to jamming as has been discovered in all guns using the recoil or gas to operate the breech block, inasmuch as 35 in the present mechanism a "snapped" cartridge will be withdrawn from the barrel as rapidly as an exploded shell.

In the accompanying drawings:

Figure 1 is a side elevation of the complete gun, the lower part of the tripod being broken away.

Fig. 2 is a front elevation thereof.

Fig. 3 is a rear elevation thereof.

Fig. 4 is a top plan view thereof.

45 Fig. 5 is a horizontal sectional view through the breeches of the rifle, showing the relative positions of the breech block mechanism.

50 Fig. 6 is an enlarged detail section taken on line 6—6 of Fig. 5, showing the parts in the position they assume when having placed a cartridge in the barrel and just previous to the exploding thereof.

Fig. 7 is a similar view to Fig. 6, show-

ing the breech block in the position it assumes after having released a spent shell and previous to the delivery of a cartridge.

Fig. 8 is a section through the frame of the mechanism substantially on the line 8—8 of Fig. 6, showing the trigger setting slots and adjacent mechanism.

Figs. 9 and 10, are detail views of various parts of the present machine gun.

Referring to the drawings, the numeral 20 designates a tripod or any support by means of which the horizontal swivel 21 may be mounted so that the mechanism may be swung from right to left, the yoke 22 supporting the rod 23, which as shown in Fig. 6, is mounted in the slot 24 to coöperate with the compression spring 25 to receive the recoil of the gun and at the same time to permit various elevations as the rod 23 provides a means for permitting vertical swinging movement of the complete mechanism. 75 The projection 26 carries the spring 25 and also the complete gun mechanism. Carried at the forward portion thereof, is the plate 27 having a plurality of interiorly threaded sockets 28 for the removable reception of the gun barrels 29. Where more than one of the barrels are employed, the sockets 28 are so arranged as to permit of a fan-like arrangement of the barrels, it being intended that at a range of 1000 yards that the bullets fired from the various barrels will be 80 18 inches apart. The barrels therefore will not be absolutely parallel.

Surrounding the barrels, either one at a time or all of them, is the water jacket 30 by means of which they are cooled. Any desired means may be employed for cooling the barrels, that here shown merely being an example of one method of doing it. The barrel carrying plate 27 is provided with a 90 plurality of pins 31 for engagement in the sockets 32, the catches 33 and pins 34 being employed to lock the same downwardly against movement, while the pins 35 are employed to prevent any forward tilting 100 movement. A bracket 36 is also employed to insure the proper locking of the parts to the frame of the machine.

Formed integral with the portion 26 and extending rearwardly therefrom, are the two 105 side plates 37 which are connected together by means of the plate 38 provided with a plurality of trigger cocking slots 39, here

shown eight in number. It will be here noted that these slots are arranged in fours in stepped relation, as in a gun of this size, eight barrels, four barrels are cocked at one time and instead of throwing the full power in the cocking operation at one time, they are operated in succession by the respective slots 39, as will presently appear.

Attached to the upper surface of the side 10 plates 37 is the top plate 40 which as here shown, is provided with the cartridge receiving apertures 41 and the reduced slots 42 for the reception of the locking lug 43 of the cartridge mechanism 44, this slot being extended from the rear of the plate 40 so a number of mechanisms may be placed in position, one after the other, the spent magazine being automatically released when it is adjacent the slot 41 to fall over or be removed by hand, as is necessary. Between the plates 38 and 40 is a heavier plate 45, which is provided with substantially dovetail shaped grooves 46, one to each breech block mechanism 47, and as each breech 15 block mechanism is a duplicate of the other, the description of one will suffice for all.

Each breech block mechanism consists of a bar 48 provided upon its under side with the rack 49, the purpose of which will presently appear, the notch 50, and with the cam end 51, while at its forward lower end it is provided with the ribs 52 and 53 for the reception of the ejector carrying block 54, which is slidably mounted thereon and limited in its forward movement by means of the slot 55 and the pin 56. In the slot 57 of the oppositely disposed wings 58 of the member 54, there are disposed the cartridge carrying and ejecting levers 59, each one of 20 which is provided with the rim engaging terminal 60 and the cam engaging operating projections 61, a spring 62 being provided to normally hold the ends 60 toward each other and in frictional engagement with the cartridge C even before the retractive movement of the breech block and after it has been seated within the groove 63 of said cartridge, the same maintaining its position even after the cartridge is within the breech 25 of the barrel, as clearly illustrated in Fig. 6. In order to release the members 59 so as to permit the empty shell to fall and assume the position as shown in Fig. 7, there is disposed in the path of the ends 61 thereof, the pins 6, Fig. 5, it being here shown in the position it assumes when some of the shells have been delivered to the breech of the barrels and the others in position for being moved forward as gripped between the ejecting 30 mechanism, the full barrel movement of the breech block causing the cartridge to assume the position as shown in the barrel with the ends 60 in engagement with the rim 63. By this means, whether the shell explodes or not and upon the retractive move-

ment of the block, it is removed from the barrel and released to receive the next cartridge above from the magazine.

Upon the upper surface of the block 47 at the forward end thereof and parallel with the ribs 52 and 53, is a tubular member 65 which guides the firing pin 66, the tubular member 65 when in breech block closing position assuming the position as shown in Fig. 6, and closing the breech while the firing pin is released. The hammer receiving head 67 is disposed at the opposite side of the guiding lug 68 of the breech block, while mounted for sliding movement to engage the same at the proper time, is the hammer 69 which consists of a substantially L-shaped plate with the terminal 70 guided under the cross-bar 71 and carrying the cylindrical rod 72 upon which is supported a spring 73 which is a compression spring and is disposed between the lug 70 and the head 69, so as to exert tension toward the firing pin. The rear end 74 of the hammer is hingedly connected as at 75 to the hammer setting and releasing block 76 which is provided with a pin 77 for fitting within the slot 78 of the setting sear 79 mounted in the slot 80 of the breech block upon the pin 81. As the breech block is retracted in its movement, the sear having its lower end 82 projected through its respective slot 39, the rear end of the slot is engaged and the end 82 moved upwardly so as to cause the block 76 to be slid rearwardly to cock the hammer, the lock 83 during this movement engaging 95 over the upper end of the cam 51 of the member 48 and assuming the position as shown in Fig. 6, with the spring 73 retracted and the hammer cocked.

In order to impart reciprocating movement to the member 48, which in reality is the breech block, there is journaled transversely of the frame, the shaft 84 which has mounted thereon two oppositely disposed toothed segments 85 and 86, whose shaft 110 here being shown as operated by the crank 87, although it is to be understood that this shaft may be operated by a spring, electric or gasoline motor as may be found desirable in practice. Also mounted upon the shaft 115 84 is a cam 87', having the oppositely disposed notches 88 and 89.

It may be said that in a gun of any number of barrels only two of these cams are employed and therefore only two of the breech block mechanisms 48 are provided with racks 49 so that when the shaft 84 is rotated these toothed segments 85 and 86 impart forward movement first to one breech mechanism and then the other. In view of 125 this fact, it is therefore necessary to have motion imparted from the respective breech blocks to the remaining ones and in order to accomplish this the racks 90 and 91 are provided upon opposite sides of the respec- 130

tive breech mechanisms so as to engage the loose pinions 92 and therefore transmit motion alternately to the various breech block mechanisms supported in the frame.

- 5 In order to lock and release the breech blocks in their extreme forward or rearward position and at the same time to release the hammers to operate upon the firing pins, there is mounted at the rear of 10 the frame two arms 93 which are guided at the rear of the frame and carry the cross-bar 94 which is adapted to sit within the notches 50 of the respective mechanisms when retracted to lock them in such position and to extend to the rear to engage the cam surface 51 of the projector mechanisms, the continued forward movement of the bar 15 94 engaging the trigger 83 to raise it from engagement in the position as shown in Fig. 20 6, so as to release the member 76 and the hammer 69 to the action of the spring 73, the parts being in absolute locked position before this occurs. The spring 95, mounted in the casing 96, and also in the hollow 25 plunger 97 which is connected to the frame 93, normally holds the cross-bar 94 upwardly. In order to release the cross-bar 94, the cam 87 is provided, the continued movement of the cam riding upon the tooth 30 98 carried by the lever 99, which is pivoted at the forward end at the slot 100 of the frame and at the rear end as at 101 to the arms 93. This action causes the depression of the arms 93 and the cross-bar 94 against 35 the action of the spring 95 so that a cross-bar is removed from the notch 50 of the retracted breech block mechanisms and from engagement with the ends 51 of the retracted mechanisms. This action takes place 40 during the time the tooth 98 is riding upon the concentric surface of the cam 87, it stopping when engaging in the notches 88 and 89, which action is only momentary but sufficiently long to permit of the shell being 45 exploded.

There is also mounted upon the frame the hinged sight 102 having the adjustable member 103.

From the foregoing description taken in 50 connection with the drawings, it is evident that any number of breech block mechanisms and barrels may be employed and may be driven from a single shell and that by means of this mechanism each alternate 55 breech block mechanism will be simultaneously retracted and the spent shell ejected while the others will be projected with the new cartridge taken from the mechanisms to be delivered in the breech of the barrels. It 60 is also evident from this construction that the action of inserting and withdrawing the cartridge and its shell is absolutely positive and that should a cartridge fail to explode it will be ejected just the same as if it had 65 exploded.

It will also be noted that with each half revolution in the main shaft that in this construction four barrels will explode and that while four are being exploded the other four are being made ready; and at the 70 completion of the revolution the remaining ones will be fired.

It is also apparent that this mechanism may be used with a single barrel or any 75 number of pairs and that any odd number also may be used as may be found desirable.

The present mechanism is so constructed and adapted as to take any of the desired calibers, that is, ranging from the rifle cartridge to the one or two pounders, in the 80 latter case a different mounting would be employed.

What I claim as new is:

1. In a machine gun, the combination of a supporting frame, a barrel attached thereto and having the breech adjacent to the frame, a sliding breech block mounted in the frame for straight line movement to and from the breech of the barrel, a firing pin and a sear carried by the breech block, 85 mechanical means for imparting reciprocation to the block, and coöperating cartridge inserting and ejecting means carried by the block and in the path thereof, whereby the cartridge is firmly grasped during insertion, 90 held during firing, and released upon retraction before the engagement of a new cartridge. 95

2. In a machine gun, the combination of a frame, two barrels connected to the frame, 100 two reciprocating breech blocks, one to each barrel mounted in the frame, a single means for imparting reciprocations to said breech blocks, a firing pin carried by each breech block, a sear also carried by each breech block, coöperative means carried by the operating mechanism and the frame for setting the firing pin and sear upon the retractive movement of the breech block and for releasing the firing pin at the end of the 105 projecting movement of the breech block, and coöperating cartridge inserting and ejecting means carried by the block and in the path thereof, whereby the cartridge is firmly grasped during insertion, held during 110 firing, and released upon retraction before the engagement of a new cartridge. 115

3. In a machine gun, the combination of a frame, two barrels connected to the frame, two reciprocating breech blocks, one to each 120 barrel mounted in the frame, a single means for imparting reciprocations to said breech blocks, a firing pin carried by each breech block, a sear also carried by each breech block, coöperative means carried by the operating mechanism and the frame for seating the firing pin and sear upon the retractive movement of the breech block and for releasing the firing pin at the end of the 125 projecting movement of the breech block, 130

and a cartridge inserting and extracting means carried by the forward end of the breech block, said latter means including resilient grips adapted to be disposed upon 5 opposite sides of the cartridge to form a guide and holder for the cartridge during the insertion thereof within the breech.

4. In a machine gun, the combination of a frame, two barrels connected to the frame, 10 two reciprocating breech blocks, one to each barrel mounted in the frame, a single means for imparting reciprocations to said breech blocks, a firing pin carried by each breech block, a sear also carried by each breech 15 block, coöperative means carried by the operating mechanism and the frame for seating the firing pin and sear upon the retractive movement of the breech block and for releasing the firing pin at the end of the 20 projecting movement of the breech block, a cartridge inserting and extracting means carried by the forward end of the breech block, said latter means including means adapted to be disposed upon opposite sides 25 of the cartridge to form a guide and holder for the cartridge during the insertion thereof within the breech, and means disposed in the path of the latter for operating the same to drop the shell after being removed from 30 the breech.

5. In a machine gun, the combination with a frame having a plurality of guides, a plurality of barrels connected at their breech to the frame, one adjacent to each 35 guide, a breech block mounted for reciprocation at each guide of the frame, a firing pin and sear carried by each breech block, means mounted in the frame and disposed in the path of the breech block for retracting the 40 firing pin and locking the same at one end of the stroke and means disposed at the opposite end of the frame for releasing the firing pin at the opposite stroke, a one direction movement means mounted in the 45 frame and connecting the breech blocks in pairs, whereby one breech block is projected and the other is retracted, means for feeding cartridges to each guide when the breech block is retracted, cartridge engaging and 50 guiding means carried by the breech block, and coöperative means in the path of the latter means for releasing the cartridge when removed from the breech.

6. In a machine gun, the combination 55 with a frame having two guides, two barrels connected at their breech to the frame, one adjacent to each guide, a breech block mounted for reciprocating in each guide of the frame, a firing pin and sear carried by 60 each breech block, means mounted in the frame and disposed in the path of the breech block for retracting the firing pin and locking the same at one end of the stroke and means disposed at the opposite end of the 65 frame for releasing the firing pin at the

opposite stroke, a transverse shaft journaled in the frame below the breech block, two oppositely disposed segments carried by the shaft, coöperative means carried by each segment and its respective breech block 70 whereby when its respective segment is engaged the breech block is moved forward, coöperative means carried by both breech blocks whereby the movement forward of one breech block imparts a rearward movement to the remaining breech block, and coöperative locking mechanism controlled by the shaft for locking both breech blocks simultaneously, one in its extreme forward and the other in its extreme rearward position. 75

7. In combination a machine gun having a reciprocable breech block, an auxiliary slideable block mounted at the forward end thereof and bodily carried by the breech 85 block, cartridge holding and extracting members carried by the latter, said members including resilient cartridge engaging means which are adapted to grip the cartridge upon opposite sides adjacent the forward end thereof and retain the same in such position until the cartridge has been pushed forward and seated within the barrel at which time such members engage the rim end of the shell and act as an extractor 90 upon the retraction of the breech block, and coöperative means disposed in the path thereof for releasing the same to permit of the dropping of a spent cartridge. 95

8. In a machine gun, the combination of 100 a frame having two guides, two breech blocks mounted therein and provided each with rack teeth upon the lower face thereof, a shaft journaled transversely of the frame, two oppositely disposed toothed segments 105 mounted upon the shaft for alternately engaging the rack bars of the breech blocks to move them in breech closing position, and coöperative means between the breech blocks whereby the movement of one breech block 110 to breech closing position moves the other breech block to breech opening position.

9. In a machine gun, the combination of 115 a frame having two guides, two breech blocks mounted therein and provided each with rack teeth upon the lower face thereof, a shaft journaled transversely of the frame, two oppositely disposed toothed segments mounted upon the shaft for alternately engaging the rack bars of the breech blocks 120 to move them in breech closing position, coöperative means between the breech blocks whereby the movement of one breech block to breech closing position moves the other breech block to breech opening position, 125 and coöperative locking means operable from the shaft, for engaging the breech blocks to momentarily lock the same in retracted or breech closing position.

10. In a machine gun, the combination 130

- of a frame having two guides, two breech blocks mounted therein and provided each with rack teeth upon the lower frame thereof, a shaft journaled transversely of the frame, two oppositely disposed toothed segments mounted upon the shaft for alternately engaging the rack bars of the breech blocks to move them in breech closing position, coöperative means between the breech blocks whereby the movement of one breech block to breech closing position moves the other breech block to breech opening position, coöperative locking means operable from the shaft, for engaging the breech blocks to momentarily lock the same in retracted or breech closing position, said latter means including a reciprocable bar guided in the frame for engaging the extreme rear or underside of the breech blocks, a lever mounted in the same and operably connected to the reciprocable bar, and a cam mounted upon the shaft for operating the lever.
11. In a machine gun, the combination of a frame having a guide way, a barrel having the breech mounted in the frame adjacent to the guide way, a breech block slidably mounted in the guide for straight line movement to and from the barrel, a slide member mounted on the barrel end of the breech block and capable of independent movement therewith, resilient cartridge engaging arms carried by the latter and adapted to receive a cartridge therebetween whereby the cartridge is held beyond the center thereof during the movement of the breech block to the barrel, the final movement of the breech block causing the slide member to be moved rearwardly in the block so that the cartridge engaging members thereof will engage the rim of the cartridge when seated in the barrel and form an extractor therefor when the breech block is retracted.
12. In a machine gun, the combination of a frame having a guide way, a barrel having the breech mounted in the frame adjacent to the guide way, a breech block slidably mounted in the guide for straight line movement to and from the barrel, a slide member mounted on the barrel end of the breech block and capable of independent movement therewith, resilient cartridge engaging arms carried by the latter and adapted to receive a cartridge therebetween whereby the cartridge is held beyond the center thereof during the movement of the breech
- block to the barrel, the final movement of the breech block causing the slide member to be moved rearwardly in the block so that the cartridge engaging members thereof will engage the rim of the cartridge when seated in the barrel and form an extractor therefor when the breech block is retracted, and coöperative means carried by the resilient cartridge engaging members and the walls of the guide way for releasing such member from engagement with the rim of the cartridge upon the retractive movement of the block.
13. In a machine gun, the combination of a frame having a guide way, a breech block slideable therein, a barrel having the breech disposed in the frame at one end of the guide way, a cartridge magazine disposed above and adjacent the inner end of the guide way, the block 54 slidably carried in the breech end of the breech block, means for holding the same in extreme forward position when the breech block is retracted, coöperating cartridge engaging means carried by the block 54 and disposed to grip the cartridge upon opposite sides intermediate of the ends thereof when received from the magazine and to engage the rim of the cartridge when the same is seated within the barrel and the block 54 is retracted within the breech block.
14. In a machine gun, the combination of a frame having a guide way, a breech block slideable therein, a barrel having the breech disposed in the frame at one end of the guide way, a cartridge magazine disposed above and adjacent the inner end of the guide way, the block 54 slidably carried in the breech end of the breech block, means for holding the same in extreme forward position when the breech block is retracted, coöperating cartridge engaging means carried by the block 54 and disposed to grip the cartridge upon opposite sides intermediate of the ends thereof when received from the magazine and to engage the rim of the cartridge when the same is seated within the barrel and the block 54 is retracted within the breech block, and coöperative means disposed in the path of the engaging means of the block 54 for operating the same to release the cartridge upon the retractive movement of the breech block.

In testimony whereof I affix my signature.
ROBERT F. HUDSON.
